ROOF TRUSS

John F. Blaski, Chicago, Ill.

Application July 8, 1942, Serial No. 450,205

4 Claims. (Cl. 108—23)

My invention relates to a roof truss and method of making the same and is particularly although not exclusively pertinent to an arched truss construction such as may be used in erecting hangars, garages and other buildings requiring large floor areas free of roof support.

An object of my invention is to provide a novel method of making a roof truss so that the tendency of a lower chord to buckle when in compression is resisted solely by the strut means between upper and lower chords.

Another object of my invention is to provide a roof truss construction with maximum strength and rigidity and with minimum material.

Another object of my invention is to provide a roof truss construction using one more upper chord than lower chord and connecting strut means so that the same perform double duty, namely, take care of the tension and compression forces between the upper and lower chords and effectively prevent the tendency of the lower chords to buckle.

Another object of my invention is to provide novel socket means for securing truss struts in place.

A further object of my invention is to provide means for maintaining the ends of boards in the laminations of the chords in connected relation to prevent endwise separation of such boards.

A still further object of my invention is to provide means for maintaining the surface alignment of the roof boards where there are no tongue and groove connections between the boards.

My invention has for a further object the provision of bolts and wedges for securing the struts in the sockets to enable the use of socket material of light weight.

A still further object of my invention is to improve generally the construction of arched roof trusses for hangars and like buildings.

The above, other and further objects of my invention will be apparent from the following description and the accompanying drawings, the views of which are as follows:

Fig. 1 is a side elevational view of an arched truss, schematically presented and illustrating the character of truss to which my invention pertains;

Fig. 2 is a fragmental top plan view of several trusses showing the arrangement of the parts and illustrating a few of the roof boards in place;

Fig. 3 is a transverse sectional view through one of the trusses taken in the plane of line 3—3 of Fig. 2;

Fig. 4 is an enlarged view, partially in section

and partially in elevation, showing socket means for securing struts to a lower chord;

Fig. 5 is a fragmental enlarged side view of a portion of a lower chord and showing side elevational appearance of the sockets for securing the struts to the chord;

Fig. 6 is a fragmental view, partially in elevation and partially in section, showing the bolt and wedge arrangement for securing a strut in a socket;

Fig. 7 is a bottom plan view, with parts in section, of Fig. 5;

Fig. 8 is a plan view of one of the bridge members used in connecting abutting ends of the planks of a lamination of a chord;

Fig. 9 is an enlarged vertical sectional view taken in the plane of line 9—9 of Fig. 8;

Fig. 10 is a fragmental plan view of adjacent roof boards showing the novel clip arrangement of my invention for maintaining these boards in surface alignment;

Fig. 11 is an enlarged elevational view of the clip as it appears when applied to an edge of one of the boards; and

Fig. 12 is a fragmental sectional view through two adjacent roof boards showing the side elevational apparatus of the clip.

The drawings will now be explained.

Referring to Fig. 3 it will be observed that a truss of my invention includes two upper chords A and B and one lower chord C. These chords are preferably laminated by tiers of boards arranged in end to end relation suitably glued and nailed together.

The lower chord C is disposed below and between the two upper chords and lies in a vertical plane which is midway between the upper chords.

A number of laminations in the upper and lower chords depends on the length of the span load to be carried by the arch and other conditions present in the construction of arched trussed roofs.

Struts 1 and 2 are connected between the upper and lower chords. As shown, the struts 1 are connected between the upper chord A and the lower chord C while the struts 2 are connected between the upper chord B and the lower chord C. As will be observed from Figs. 2, 3 and 5 these struts are inclined to the vertical as well as to the horizontal. While these struts might be bolted directly to the chords, I prefer to utilize sockets for receiving the ends of the struts in their connections to the chords.

Referring to Figs. 4 and 5, plates 3 and 4 have over-turned top flanges 5 and 6 respectively

adapted to be bolted to the sides of the chords. The plate 3 has a marginal portion 7 offset with respect to the plane of the plate so as to overlie an adjacent margin 8 of the plate 4, as is illustrated in Figs. 5 and 7. Welded to the plate 3 is a socket 9, and welded to the plate 4 is a socket 10. These sockets are illustrated as rectangular in cross section although it is to be understood that they might be circular or polygonal as desired.

The sockets are so welded to their plates as to incline the struts in the desired angular relation to secure maximum strength between the chords. The sockets for the plates used with the lower chord are closed at their bottoms and the sockets for the plate used with the upper chords are closed at their tops. I have found that it is feasible to securely attach the struts within the sockets by a single bolt per socket when using wedge-shaped washers.

Fig. 6 shows a fragmental portion of a socket and a sectional portion of an inserted strut. The socket is apertured to receive a bolt 11 and two opposite faces of the strut are cut out as at 12 and 13 to receive wedge-shaped washers 14 and 15. The washers are apertured at 16 to receive the bolt and are arranged within the cut-out portions of the strut as illustrated in Fig. 6. It will thus be observed that when tension or compression forces are applied to a strut tending to move it relatively to its socket the load will be spread over the face engagement of the washers and the strut, thus increasing the holding effect and reducing the tendency of wear in the bolt aperture. When the sockets are made of relatively thin material, increased bearing engagement for the bolt is achieved by application of collars 17 and 18 to the outer surface of a socket and in register with the bolt apertures, which collars are welded in place. There is accordingly provided ample bearing surface between the bolt and socket to resist shear stresses.

The socket plate 3 is provided with an aperture to receive a securing bolt 19, while the plate 4 is apertured to receive a securing bolt 20. The overlapping portions 7 and 8 of the face are apertured to receive securing bolts 21 and 22. In applying the plates to a chord, washers 14 are applied over the bolts against the side surfaces of the chord and as the bolts are tightened the washers are pressed into engagement with the chords, indenting the chords to provide cooperating seats for the washers. I have found that this manner of attaching the plates is satisfactory and is one which prevents loosening of the plates.

In order to prevent endwise separation of the planks in the laminations of the chords I have provided novel bridge means. Such means are illustrated in Figs. 8 and 9 and include two similar bridge plates 23 and 24 made of a suitable thickness of sheet metal. Prongs or teeth 25 and 26 are struck out of the plates. When the adjacent ends of planks such as 27 and 28 are to be connected, the bridge plate 23 is placed over the side surfaces of adjacent ends of the planks and another plate 24 on the bottom. The ends of the planks are brought together and then the two plates are hammered so that the prongs or teeth 25 and 26 enter the planks thus securing the ends together against separation.

My invention contemplates the application of roof boards 29 directly to the upper chords of the trusses so that the roof boards thus become integral parts of the trusses and brace the upper chords, holding them in place.

Because of present restrictions in the manufacture of lumber, it is impossible to obtain tongued and grooved material. To maintain surface alignment of the roof boards 29 I therefore provide novel clips, one of which is illustrated in Figs. 10, 11 and 12. A clip is fashioned from metal of suitable thickness and comprises a central body 30 having upper and lower ears 31 and 32 projecting at right angles to the body on one side of the same and another pair of ears 33 and 34 bent in the opposite direction. Struck out of the body between its ends and extending in opposite directions therefrom are teeth 35 and 36. When used to maintain surface alignment of the boards these clips are placed between the adjacent side margins of the boards and the boards forced together. The clips 31, 32, 33 and 34 engage the outer surfaces of the boards while the teeth 35 and 36 enter the boards through their side margins, thus maintaining the surface alignment of the boards. The lengths of the clips and teeth are such as to maintain surface alignment of the boards under expansion and contraction due to weather conditions.

It will be observed that the truss construction of my invention provides a truss which is rigid and strong and made up from a minimum amount of material, by reason of the fact that one lower chord is so connected to two upper chords as to brace the lower chord against any tendency to buckle should the lower chord be in compression. Such construction eliminates the lateral braces heretofore employed between the lower chords of trusses constructed with the lower chords in vertical alignment with the upper chords.

It will be observed also that the struts of my truss construction function to take care of compression and tension stresses between the upper and lower chords and also constitute the sole means for resisting buckling of the lower chords.

Instead of using wood struts as described, pipe might be substituted. Such pipe struts might be used with the sockets described, or the sockets might be eliminated and the pipe bolted directly to the chords.

It will be noted that the number of plies in the lower chord C of Fig. 3 is greater than the number of plies in the lower chord illustrated in Figs. 4 and 5. Figs. 4 and 5 are illustrative of the manner of securing the socket plates to the chords, the number of plies in a chord making no difference as to the manner of applying the plates to the chord. In Fig. 3 it will be observed that the socket plates extend only part way down the lower chord C. The extent of such plates depends, of course, on the depth of the chord.

The method of my invention contemplates making a roof truss so that the tendency of the lower chord to buckle when in compression is resisted solely by the struts between the upper and lower chords and so disposing the upper and lower chords with a lower chord below and between two upper chords and connecting each of the upper chords with the lower chords by struts which are inclined to a vertical plane including the lower chord.

While my invention has been illustrated in connection with an arched truss, the same construction could be employed in making a straight truss.

Prior to the application of the struts to the sockets the struts are suitably waterproofed by paint or chemical substances to prevent undue expansion and contraction of the struts incidental to weather variations. Such waterproofing

of the struts prevents loosening of the struts with respect to the chords, thus maintaining the rigidity and strength of the trusses.

I do not intend to limit the invention to the details of construction shown and described except only in so far as certain of the appended claims may be specifically so limited, as it will be obvious that modifications may be made without departing from the principles of the invention.

I claim:

1. A truss roof comprising a plurality of spaced pairs of upper chord members, a lower chord member disposed intermediate the upper chord members of each pair in such lateral offset relation that no upper and lower chord members lie in the same vertical plane, struts connecting the upper and the lower chord members and being inclined to the length of the chords and also to the vertical whereby the same struts that are subjected to compression and tension forces of the upper and lower chords function to prevent buckling of a lower chord when the same is in compression, and roof boards attached to said upper chord members spanning the spaces between adjacent trusses and the spaces between the upper chord members of each truss to provide an unbroken roof surface, said roof boards effecting lateral bracing of said upper chord members.

2. A truss roof construction in which lateral bracing of the lower chords is effected solely by the truss struts, each truss comprising two upper chords and one lower chord disposed between and below said two upper chords, and struts connecting each upper chord with said lower chord,

said struts being inclined to the vertical and horizontal in such manner that the horizontal components of forces act to prevent buckling of the lower chord when the latter is in compression, said trusses being disposed in laterally spaced relation, and roof boards attached to said upper chords spanning the spaces between adjacent trusses and the spaces between the upper chords of each truss to effect lateral bracing of said upper chords.

3. A roof truss comprising two parallel and laterally spaced upper chords, one lower chord disposed in a vertical plane midway between the two upper chords, and struts connecting each of the upper chords with the lower chord whereby the same struts function in compression and tension between the upper and lower chords and also prevent buckling of the lower chord when it is in compression.

4. In a roof truss comprising two parallel and laterally spaced upper chords, one lower chord disposed in a vertical plane midway between said two upper chords, a plurality of struts for connecting each of the upper chords with the lower chord, means for connecting the struts to the lower chord comprising plates attached to the side surfaces of said lower chord, sockets secured to said plates with the lengths thereof inclined to the horizontal and vertical, a bolt passing through a socket and its strut, and means for relieving forces of compression and tension on the bolt by a strut comprising wedge washers acting against opposite faces of a strut.
